DESIGN FOR A MILKING PARLOR STALL UNIT

Henry B. Babson, Chicago, and Chester A. Thomas, Crystal Lake, Ill., assignors to Babson Bros. Co., a corporation of Illinois

Application January 5, 1944, Serial No. 112,170

Term of patent 14 years

(Cl. D12—5)

To all whom it may concern:

Be it known that we, Henry B. Babson and Chester A. Thomas, citizens of the United States, residing at Chicago and Crystal Lake, respectively, in the counties of Cook and McHenry, respectively, and State of Illinois, have invented a new, original, and ornamental Design for a Milking Parlor Stall Unit, of which the following is a specification, reference being had to the accompanying drawings forming a part thereof, in which:

Figure 1 is a front elevational view of a milking parlor stall unit, showing our new design;

Figure 2 is a plan view of the stall;

Figure 3 is a rear elevational view of the same stall; and

Figure 4 is an end elevational view of the stall.

We claim:

The ornamental design for a milking parlor stall unit, as shown.

HENRY B. BABSON.
CHESTER A. THOMAS.
